UNITED STATES PATENT OFFICE.

WESTERN UNDERWOOD, OF SANTA MONICA, CALIFORNIA.

DESIGN FOR A LAMP GLOBE.

Application filed May 11, 1925. Serial No. 13,394. Term of patent 7 years.

To all whom it may concern:

Be it known that I, WESTERN UNDERWOOD, a citizen of the United States, residing at Santa Monica, in the county of Los Angeles and State of California, have invented new, original, and ornamental Design for Lamp Globes, of which the following is a specification, reference being had to the accompanying drawings, forming part thereof.

Fig. 1 is a perspective view of the globe; and Fig. 2 is a perspective view of the globe showing it on a smaller scale and from a different angle.

I claim:

The ornamental design for a lamp globe as shown.

WESTERN UNDERWOOD.
